United States Patent Office

Des. 210,646

Patented Mar. 26, 1968

210,646

CAMERA CASE

Donald E. Everburg, Southbridge, Mass., assignor, by mesne assignments, to American Optical Company,
Southbridge, Mass., a corporation of Delaware

Filed June 15, 1966, Ser. No. 2,681

Term of patent 7 years

(Cl. D87—5)

FIG. 1 is a front, top and side perspective view of a camera case, showing my new design in closed position;

FIG. 2 is a rear, top and opposite side perspective view in opened position; and

FIG. 3 is a rear elevational view thereof in closed position.

The dominant features of my new design are shown in solid lines in the drawing.

I claim:

The ornamental design for a camera case, as shown and described.
